SELF COOLING BED AND COUCH CUSHION

Filed Sept. 15, 1934

UNITED STATES PATENT OFFICE

2,103,553

SELF-COOLING BED AND COUCH CUSHION

Joseph H. Reynolds, Cisco, Tex.

Application September 15, 1934, Serial No. 744,103

1. Claim. (Cl. 155—182)

This invention relates to new and useful improvements in self-cooling bed and couch cushions.

One object of the invention is to provide a cushion arranged to be placed over the mattress of a bed, or padding of a couch, whereby a circulation of air may be provided between the body of the person resting upon the cushion and the mattress or padding of the bed or couch, thus making for comfort and tending to eliminate body distresses resulting from various causes.

A further object of the invention is to provide a cushion of the character described, including a plurality of absorbent wicks which may be saturated with water, thus making the cushion self-cooling.

Still another object of the invention is to provide a cushion adapted to be spread over a mattress or the like, and arranged to be conveniently folded when not in use; together with pockets for receiving the cooling and supporting units.

A still further object of the invention is to provide a metallic cooling unit including a flexible frame adapted to yield to the weight of the body of the person reclining thereon, and including two sets of coiled springs connected at their inner ends to a flexible supporting member, whereby the required resiliency and flexibility is given to the unit, without undue sagging of the coiled springs.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a view of a cushion constructed in accordance with the invention, partly in plan and partly in section,

Figure 2 is a longitudinal sectional view taken on the line 2—2 of Fig. 1,

Figure 3 is a detail showing a portion of one of the supporting units,

Figure 4 is a transverse sectional view taken on the line 4—4 of Fig. 3,

Figure 5 is a transverse sectional view taken on the line 5—5 of Fig. 3, and

Figure 6 is a transverse sectional view taken on the line 6—6 of Figure 3.

Figure 7 is a view showing the cushion folded.

In the drawing the numeral 10 designates a metallic supporting unit of which several are employed in making up the cushion. I have illus-

trated four of these units enclosed in a fabric cover or casing 11, however the invention is not to be limited to the number of units used.

Each unit comprises a marginal rectangular frame 12, preferably formed of stout, galvanized wire, having its ends suitably fastened or welded together. Around each end of the frame 12 is bent a clip 13 which is made of a strip of metal bent upon itself around the frame, as is shown in detail in Fig. 5, and its end portions brought together to form a flange 14. The end coils 15 of coiled springs 16 are engaged in eyes or apertures 17 formed in each of the flanges, whereby the springs are attached to the frame. It will be noted that each spring is considerably larger in diameter than the frame and the clip, and therefore each spring will project above and below the frame, thus supporting it above the surface on which the springs rest.

There are two sets of springs in each frame, each set having its outer ends connected to the flanges 14. For supporting the inner ends of the springs a flexible metal strip or bridle 18 is fastened transversely across the mid-portion of the frame 12. The ends of this strip are secured in clips 19 similar to the clips 13 fastened around the frame. This metal strip is provided along each edge with eyes 20 for receiving the end coils 21 of the coiled springs 16. It is important that the strip 18 be sufficiently flexible and resilient to permit a free up-and-down movement of the ends of the springs, so as to yield to the body and thereby make for maximum comfort.

In each spring is inserted an elongated wick 22. It is preferable to make these wicks of soft felt, and to allow sufficient space for the wicks to expand when saturated. Owing to the difference in the size of the springs and the frame, these wicks may be inserted into the ends of the springs after the unit has been assembled. By immersing the unit in water, the wicks will be moistened and will become saturated to the fullest extent. It has been found that by shaking the unit and dropping it upon a hard surface, the excess water is removed, and so long as the wicks are maintained horizontally, they will not exude moisture. This permits the unit to be inserted in the cover 11 without leaking water.

The cover 11 is rather unique in structure, being formed of a strip A of very coarse fabric. The end portions of this strip are turned upon themselves to form pockets B and flaps C. A unit 10 is inserted in each pocket B, and the flap C is tucked in between the unit and the back strip A. A separate piece of the same fabric D

is double-stitched at E across the center of the cover to form a hinge joint and to provide two pockets facing the pockets B and provided with flaps F used similarly to the pockets B when the units 10 are placed in the pockets D.

5 The longitudinal edges of the pockets are secured with a suitable binding tape G, whereby the cover is given a proper finish. Sufficient space is left between the pockets B and D to provide a 10 hinge so that the cover may be folded, as shown in Fig. 7. The cover is very simply constructed and the units are held without the use of fastenings.

It has been found that a cushion of this type 15 not only cools and ventilates the body, but is very comfortable because the springs have a tendency to roll when the body is moved, and this greatly adds to the comfort. The use of this cushion tends to eliminate bed sores and other body 20 discomforts resulting from confinement to the bed, and is particularly useful in hospitals.

What I claim and desire to secure by Letters Patent is:

In a bed or couch cushion of the character described and comprising a pocketed casing of flexible sheet material, a cushioning and cooling unit

insertable interchangeably in the respective pockets of the casing, comprising, a rectangular body frame of relatively stout wire, said frame having at opposite ends a strip of sheet metal folded longitudinally therearound with its marginal portions brought together to provide a flange, said flange being provided with a series of apertures throughout the length thereof, a bridle strip of flexible sheet metal extending across said frame from side to side thereof and medially between 10 said flanged end strips and having apertures at its opposite marginal portions and respectively aligned with the apertures of said flanged end strips, helical springs secured at their outer ends in the apertures of said flanged end strips and 15 at their inner ends in the apertures of said medial bridle strip, said springs being each of the same diameter and the diameter being relatively greater than the diameter of the constituent wire of the body frame and also greater than the thickness of the bridle strip, the axes of the frame wire, bridle strip and each of the springs being in substantially the same plane, and a wick element in each of said springs.
